(57) **CLAIM**

The ornamental design for an atomizer for electronic cigarette, as shown and described.

DESCRIPTION

FIG. 1 is a perspective view of an atomizer for electronic cigarette showing a first embodiment of my new design shown as component 1 removed from the assembly in FIGS. 27-34 for clarity of disclosure;

FIG. 2 is another perspective view thereof;

FIG. 3 is a front elevation view thereof;

FIG. 4 is a rear elevation view thereof;

FIG. 5 is a left side view thereof;

FIG. 6 is a right side view thereof;

FIG. 7 is a top view thereof;

FIG. 8 is a bottom view thereof;

FIG. 9 is a partial enlarged view showing the part indicated by reference numeral 9 in FIG. 1;

FIG. 10 is a perspective view of an atomizer for electronic cigarette showing a second embodiment of my new design shown as component 2 removed from the assembly in FIGS. 35-42 for clarity of disclosure;

FIG. 11 is another perspective view thereof;

FIG. 12 is a front elevation view thereof;

FIG. 13 is a rear elevation view thereof;

FIG. 14 is a left side view thereof;

FIG. 15 is a right side view thereof;

FIG. 16 is a top view thereof;

FIG. 17 is a bottom view thereof;

FIG. 18 is a partial enlarged view showing the part indicated by reference numeral 18 in FIG. 10;

FIG. 19 is a perspective view of an atomizer for electronic cigarette showing the first embodiment and the second embodiment of my new design shown as component 3 removed from the assembly in FIGS. 27-34 and FIGS. 35-42 for clarity of disclosure;

FIG. 20 is another perspective view thereof;

FIG. 21 is a front elevation view thereof;

FIG. 22 is a rear elevation view thereof;

(Continued)

FIG. 23 is a left side view thereof;
 FIG. 24 is a right side view thereof;
 FIG. 25 is a top view thereof;
 FIG. 26 is a bottom view thereof;
 FIG. 27 is a perspective view of an atomizer for electronic cigarette showing the first embodiment of my new design where the component 1 and the component 3 are shown in an assembled state of use;
 FIG. 28 is another perspective view thereof;
 FIG. 29 is a front elevation view thereof;
 FIG. 30 is a rear elevation view thereof;
 FIG. 31 is a left side view thereof;
 FIG. 32 is a right side view thereof;
 FIG. 33 is a top view thereof;
 FIG. 34 is a bottom view thereof;
 FIG. 35 is a perspective view of an atomizer for electronic cigarette showing the second embodiment of my new design where the component 2 and the component 3 are shown in an assembled state of use;
 FIG. 36 is another perspective view thereof;
 FIG. 37 is a front elevation view thereof;
 FIG. 38 is a rear elevation view thereof;
 FIG. 39 is a left side view thereof;
 FIG. 40 is a right side view thereof;
 FIG. 41 is a top view thereof; and
 FIG. 42 is a bottom view thereof.

The dash-dash lines show portions of the atomizer for electronic cigarette that form no part of the claimed design. The short-long-dash lines in FIGS. 1, 9, 10, and 18 show the boundary of the enlarged views and forms no part of the claimed design.
